(57) **CLAIM**

The ornamental design for a pet carrier, as shown and described.

DESCRIPTION

FIG. 1 is a perspective view of a pet carrier design showing my new design.

FIG. 2 is a front view of a pet carrier.

FIG. 3 is a rear view of a pet carrier.

FIG. 4 is a left side view of a pet carrier.

FIG. 5 is a right side view of a pet carrier.

FIG. 6 is a top view of a pet carrier; and,

FIG. 7 is a bottom view of a pet carrier.

The broken line in the drawings illustrate portions of the pet carrier that form no part of the claimed design.
